ABSTRACT OF THE DISCLOSURE

An article addressing machine having label transfer means to bring individual labels into transfer contact with articles to be addressed and transfer address information from the address to the article, including means for accumulating the used labels and means for withdrawing the used labels, delivering them to the transfer means, applying glue to the labels and applying the labels to articles.

This is a division of application Ser. No. 505,930, filed Nov. 1, 1965.

This invention relates to an addressing machine and particularly one which is capable of cutting elongated label sheets into individual labels and then heat transferring addresses or the like from the labels to articles and/or gluing the labels to articles, all accomplished automatically.

One object of the invention is to provide an addressing machine having a fully adjustable article magazine from which articles are removed one at a time by a reciprocating vacuum plate and delivered to a timing belt which propels the articles past a vacuum and heat transfer wheel and then to a take-away conveyor where the articles are singled for ready packaging.

Another object is to provide a fully adjustable label sheet feeding and shearing assembly which shears a label sheet into strips and then cuts the strips into individual labels before using them for imprinting addresses or the like on letters, magazines or the like.

Still another object is to provide automatic label sheet feeding means, label strip feeding means, label feeding means and heat transfer means for transferring indicia from individual labels to envelopes or the like, and means for then accumulating the labels so that they can be later glued to other envelopes or the like.

A further object is to provide a readily adjustable means for insuring that only one article at a time will be removed from an article magazine and for the proper feed thereof from the magazine to the timing belt of the machine, means for adjusting the machine so that the imprint on the envelope can be placed as desired both longitudinally and laterally of the envelope, and means for adjusting the machine for different thicknesses of articles to be labeled.

An additional object is to provide a pair of one-way clutch arrangements to permit manual inching of the machine during adjustments without the necessity of having to rotate the motor of the machine during such inching.

Another additional object is to provide a spring wire finger arrangement to guide a label strip properly into cutting rollers which cut it into individual labels.

Still another additional object is to provide a simple gearing arrangement for driving various components of our machine in properly timed relation.

A further additional object is to provide an arrangement whereby the machine can be readily converted from a heat transfer operation to a label glue-on operation with a minimum change of parts.

Still a further additional object is to provide a ma-

2

chine which can label articles such as envelopes, magazines or the like in one or both of two ways:

(1) Printing addresses on the articles by heat transfer from individual labels, and/or

5 (2) Gluing the labels with the addresses thereon onto the articles.

With these and other objects in view, our invention consists in the construction, arrangement and combination of the various parts of our addressing machine, whereby the objects above contemplated are attained, as hereinafter more fully set forth, pointed out in our claims and illustrated in detail on the accompanying drawings, wherein:

FIG. 1 is a perspective view of an addressing machine embodying our invention and showing the front thereof;

FIG. 2 is a similar perspective view showing the back thereof;

FIG. 3 is an enlarged vertical sectional view of the upper portion thereof on the line 3—3 of FIG. 1;

20 FIG. 4 is a further enlarged sectional view on the line 4—4 of FIG. 3 showing a detail of the machine;

FIG. 5 is a side elevational extension of the lower end of FIG. 3 with a portion of a cover door broken away to show internal mechanism;

25 FIG. 6 is a plan view of part of the machine as indicated by the line 6—6 of FIG. 3;

FIG. 7 is an enlarged vertical sectional view on the line 7—7 of FIG. 6;

30 FIG. 8 illustrates a portion of FIG. 7 with the parts in a different position;

FIG. 9 is a horizontal sectional view on the line 9—9 of FIG. 7 to show a gearing arrangement;

FIG. 10 is a detail sectional view on the line 10—10 of FIG. 7;

35 FIG. 11 is an enlarged vertical sectional view on the line 11—11 of FIG. 6;

FIGS. 12 and 13 are vertical sectional views on the lines 12—12 and 13—13, respectively, of FIG. 11;

FIG. 14 is a horizontal sectional view on the line 14—14 of FIG. 11;

FIG. 15 is an enlarged vertical sectional view on the line 15—15 of FIG. 3;

40 FIGS. 16 and 17 are vertical sectional views on the lines 16—16 and 17—17, respectively, of FIG. 15 showing certain limit switches of the machine;

FIG. 18 is an enlarged vertical sectional view on the line 18—18 of FIG. 3;

FIG. 19 is an enlarged vertical sectional view on the line 19—19 of FIG. 3;

50 FIG. 20 is an enlarged vertical sectional view on the line 20—20 of FIG. 3;

FIG. 21 is an enlarged vertical sectional view on the line 21—21 of FIG. 6 showing an inching knob;

FIG. 22 is a vertical sectional view on the line 22—22 of FIG. 21;

FIG. 23 is an enlarged vertical sectional view on the line 23—23 of FIG. 3 showing a motor pulley clutch;

FIG. 24 is a vertical sectional view on the line 24—24 of FIG. 23;

60 FIG. 25 is an enlarged plan view of a take-away conveyor shown at the right-hand end of the machine in FIG. 1 and at the left-hand end in FIG. 2;

FIG. 26 is a vertical sectional view on the line 26—26 of FIG. 25;

65 FIG. 27 is a vertical sectional view on the line 27—27 of FIG. 26;

FIG. 28 is an enlargement of a portion of FIG. 3 shown mainly in elevation but with certain parts broken away and other parts shown in vertical cross section;

70 FIG. 29 is a further enlargement of a portion of the right-hand end of FIG. 28 shown in vertical cross section instead of side elevation as in FIG. 28;

FIG. 30 is an elevation of the portion of the machine shown in FIG. 28, shown from the reverse side;

FIG. 31 is a vertical sectional view on the line 31—31 of FIG. 30;

FIG. 32 is an enlargement of a portion of FIG. 30 shown within the dot-and-dash line circle 32, some parts being shown in vertical cross section;

FIG. 33 is an end elevational detail in accordance with the arrow 33 adjacent the right-hand end of FIG. 30;

FIG. 34 is a vertical sectional view on the line 34—34 of FIG. 30;

FIG. 35 is an enlarged sectional view on the line 35—35 of FIG. 30;

FIG. 36 is a sectional view on the line 36—36 of FIG. 35;

FIG. 37 is a view similar to a portion of FIG. 30 showing a gearing arrangement between operating elements of the machine;

FIG. 38 is an enlarged horizontal sectional view on the line 38—38 of FIG. 37;

FIG. 39 is a vertical sectional view on the line 39—39 of FIG. 38;

FIG. 40 is an elevation in accordance with line 40—40 of FIG. 39;

FIG. 41 is a sectional view on the line 41—41 of FIG. 39;

FIG. 42 is a vertical sectional view on the line 42—42 of FIG. 38;

FIG. 43 is an enlarged vertical sectional view on the line 43—43 of FIG. 37;

FIG. 44 is an enlarged horizontal sectional view on the line 44—44 of FIG. 37;

FIG. 45 is a vertical sectional view on the line 45—45 of FIG. 44;

FIG. 46 is a plan view of a portion of FIG. 37 as indicated by the line 46—46 thereadjacent;

FIG. 47 is a vertical sectional view on the line 47—47 of FIG. 37;

FIG. 48 is an enlarged vertical sectional view on the line 48—48 of FIG. 46;

FIG. 49 is an enlarged vertical sectional view on the line 49—49 of FIG. 48, a portion of a vacuum pick-off wheel being broken away and another portion thereof being shown in section;

FIG. 50 is a vertical sectional view on the line 50—50 of FIG. 48;

FIG. 51 is a diagrammatic view similar to a portion of FIG. 28 to show a label feeding operation;

FIG. 52 is a similar diagrammatic view to show a label pick-up and heating operation and label cutting and discharge operations;

FIG. 53 illustrates diagrammatically how a label sheet is trimmed, cut into strips, then cut into individual labels and placed on an envelope by means of our labeling machine;

FIG. 54 shows the carbon side of a label shown in FIG. 53, the address thereon being heat-transferable to an envelope;

FIG. 55 shows the address transferred from the label to an envelope;

FIG. 56 shows the label then used on a second envelope;

FIG. 57 is a view similar to a portion of FIG. 28 showing the addition of a glue pot to the machine for gluing labels instead of heat transferring the address from the label to the envelope as in the previous figures;

FIG. 58 is a horizontal sectional view on the line 58—58 of FIG. 57;

FIG. 59 is an enlarged sectional view on the line 59—59 of FIG. 57, and

FIG. 60 is an opposite face view of a vacuum valve disc shown in FIG. 57.

On the accompanying drawings we have used the reference numeral 10 to indicate, in general, a housing for our machine which has a table-like top 12. Referring to FIG. 3, a magazine for articles is provided at the left-hand end of the housing 10 comprising a front wall 14, side walls 75

16 and 18 and a back wall 20 adapted to contain envelopes, magazines or the like to be labeled by printing addresses or the like thereon and/or gluing labels on which addresses are printed to the envelopes or magazines. The article magazine 14, 16, 18, 20 is adjustable to accommodate different sizes of envelopes or the like. The side walls 16 and 18 are mounted on magnets 17 for this purpose, the top 10 being of ferrous material so that magnets will remain where placed thereon.

10 A feeding mechanism for removing the articles one at a time is provided as shown in FIGS. 3, 4, 7 and 8, and comprises a bracket 22 supporting a pair of rods 24 on which depending hubs 27 of a slide plate 26 are slidably, the slide plate being slid by a connecting rod 28 and a crank pin 30. The crank pin 30 is carried by a crank arm 32 on a shaft 34 as shown in FIG. 9, the shaft 34 being driven by means which will hereinafter be described. The rear or left-hand end of the slide plate 26 is provided with an envelope engaging finger 35 carried by a plate 36 while the front end thereof is provided with a vacuum plate 38 mounted on a plate 39 secured to the slide plate 26. The machine can be adjusted for article-removing operation by either the finger 35 or the vacuum plate 38. A vacuum slide valve 40 is associated with the plate 39 as shown in FIGS. 7 and 8.

15 The slide valve 40 is in frictional engagement with the plate 39 which has a vacuum cavity 44 to which a vacuum hose 46 leads. A bracket 47 confines the valve 40 loosely in position whereas it is frictionally engaged by atmospheric pressure against the plate 39 when the vacuum is in effect. A valve actuating rod 50 mounted on the bracket 22 actuates the slide valve 40 and a pair of set collars 52 on the valve rod 50 provide a lost-motion connection with a bracket 42 of the slide valve 40 to effect reciprocations 20 of the slide valve so that vacuum comes "ON" in the retracted position of FIG. 7 and is turned "OFF" in the forward position of FIG. 8.

25 Envelopes 54 are shown in the article magazine 14, 16, 20 shown in FIGS. 7 and 8, and are adapted to be propelled by the vacuum plate 38 to timing belt 56. If the machine is adjusted for article withdrawal by the finger 35 the finger is adjusted to a projecting position (shown dotted) so that it will engage the rear edge of the envelope to insure such withdrawal. Adjustment is effected by loosening a screw 37 whereupon the finger is raised by a spring 41 to such projecting position.

30 A light spring 48 is connected with the bracket 42 to keep it against the rear collar 52 during return of the rod 50 to the position of FIG. 8 if there is no envelope 54 on the vacuum plate 38, thus minimizing the load on the vacuum hose 46. As shown in FIGS. 3 and 6, a rod 120 extends from the magazine front wall 14 to support an electric eye 122 to automatically shut down operation of the machine when there is a misfeed.

35 The envelopes are then carried by the timing belt 56 under leaf spring loaded hold-down rollers 58 to a vacuum and heat transfer wheel 60, the position of which is shown by dot-and-dash lines in FIG. 6. The timing belt 56 extends around a forward pulley 62 and a rearward pulley 64. The pulley 62 is on a shaft 66 driven from a shaft 68 by a belt 70 as shown in FIGS. 3, 15 and 18. The shaft 68 is in turn driven by a belt 72 from a pulley 74 of a gear reducer 76 driven by a motor 78.

40 In FIGS. 1 and 6 we show an "inch" knob 336 mounted on the shaft 68 as shown in FIG. 15. A legend "INCH" is shown in FIG. 6 to indicate the purpose of the knob. Legends "START" and "STOP" also appear to the left of the "INCH" legend which controls switches for the starting and stopping of the entire machine.

45 Details of the inching knob are shown in FIGS. 21 and 22 wherein the shaft is shown as provided with cam surfaces to coact with rollers 338 to provide a one-way clutch which permits the knob to rotate the shaft in only one direction in an obvious manner. The direction of rotation 50 of the shaft 68 is clockwise as indicated by the arrow a

and in doing so the rollers are loose so that the knob can remain stationary under the friction of a leather washer 340 while the labeling machine is running. When the machine is idle and adjustments or the like are required, rotation of the knob 336 in the direction of the arrow *a* will cause the rollers to bind in a hub 337 of the knob and the shaft 68 can accordingly be rotated in the proper direction.

The pulley 74 as shown in FIGS. 23 and 24 is mounted on a shaft 73 of the gear reducer 76 with a one-way clutch connection between the two comprising a cam sleeve 75 and one-way rollers 77. The shaft rotates clockwise as indicated by the arrow *a* and thereby drives the pulley 74. Whenever the motor 78 is de-energized but it is desirable to manually "inch" the machine in the forward direction, such inching can be accomplished by the inching knob 336 without having to rotate the shaft 73 and the motor 78 since the pulley 74 can rotate freely in the direction of the arrow *a*.

Opposite the heat transfer wheel 60 a resilient roller 80 is provided on an idler shaft 82 as shown in FIGS. 3, 6, 20 and 37. The roller 80 has an open portion as shown in FIG. 20 for the timing belt 56 and the shaft 82 has a timing pulley 84 thereon for driving the resilient roller 80 from the timing belt 56 and at the same surface speed as the belt. The roller 80 is elongated as shown in FIGS. 6 and 20 to accommodate different widths of envelopes or magazines without the necessity of adjustment, and a portion of its upper periphery projects through a slot 81 in the top 12 of the machine.

Referring to FIGS. 7 and 9, the crankshaft 34 is driven by a pair of gears from an idler shaft 86 which in turn is driven by a pair of gears from the rear pulley 64 of the timing belt 56. A second idler shaft 86 is also driven by a pair of gears from the crankshaft 34 and by means of a timing belt 88 drives a coupling member 90 shown in FIGS. 7 and 11 and coacting with a coupling member 92 which drives a feed roller 94. The feed roller 94 coacts with a resilient land 96 on a feed roller 98 mounted on the shaft 34 vertically below the roller 94, and the rollers 94 and 98 pick up the envelope 54 in the forward position of the slide plate 26 shown in FIG. 8 and deliver it to the timing belt 56 and the hold-down rollers 58.

Means is provided for vertically adjusting the feed roller 94 by mounting it on a slide 100 shown in FIGS. 11 and 13 and which has a tapered flange 101 normally biased downwardly by a spring 102 against a wedge 104 which may be adjusted laterally by a screwthreaded adjusting rod 106 terminating in an adjusting knob 108.

As shown in FIGS. 11 and 12, the front wall 14 of the article magazine 14, 16, 18, 20 is provided with a vertically adjustable stop bar 110 which can be nicely adjusted with respect to the vacuum plate 38 to accommodate various thicknesses of envelopes, magazines and the like by a second wedge 112, screwthreaded rod 114 and knob 116. A spring 118 engages a tapered flange 109 from the stop bar 110 with the wedge 112.

The envelopes 54 are adapted to be fed one at a time from the article magazine 14, 16, 18, 20 to the timing belt 56 which carries them under the vacuum and heat transfer wheel 60 and then discharges them into a collecting unit 124 shown in FIGS. 1 and 2. At the wheel 60 an address is adapted to be transferred from a label to the envelope, or a label with the address thereon is adapted to be glued to the envelope depending on the way the machine is set up for operation as will herein-after appear.

The labels referred to are shown in FIG. 53 as first a printed label sheet 126, then a printed label strip 128 and finally a single printed label 130. The sheet 126 as it enters our machine has perforated margins 132 which are sheared therefrom by rotary knives 134, then the label strips 128 are sheared therefrom along a line 135 as by a vertically reciprocating knife 136 and the label strip 128 is thereafter cut as indicated at 138 into indi-

vidual labels 130. The means for supporting the label sheets 126, and the knives 134 and 136 and associated mechanism will now be described.

Referring to FIGS. 18 and 28 to 37, inclusive, a main bracket 5 is shown generally at 140 which is both vertically and horizontally (laterally of the machine) adjustable. The means for supporting the bracket and effecting such adjustment will now be described. The bracket 140 is supported on a vertical slide 248 (see FIG. 18) by means of a spacer bracket 250. A horizontal slide 252 is supported by a horizontal slide way 254 and carries a vertical slide way 256 for the vertical slide 248. The horizontal slide 252 is adjusted by an adjusting screw 258 terminating in an adjusting knob 260 at the front of the machine as shown in FIG. 1. Also, at the front of the machine is a vertical adjusting knob 262 which is operatively connected through a telescoping shaft 264 with a vertical adjusting screw 268 by means of bevel gears 266.

The main bracket 140 has side plates 139 and 141 (see FIGS. 28 and 30) supporting five idler wheels 155 on a shaft 157 under which the label sheet 126 extends and then up over two supporting wheels 154, two supporting wheels 154^a and two drive sprockets 144. The sprockets have their teeth engaging in the perforations of the margins 132. The shaft 157 is carried by pivoted arms 159 which are normally held in the position shown in FIG. 34 by magnetic latches 161 which permit quick disengagement of the wheels 155 from the sheet 126 in case of malfunctioning, and equally quick return of the wheels to normal position. Two hold-down rollers 146^a and two hold-down wheels 146 coact with the top of the sheet 126 and are mounted on a shaft 152 which also carries the rotary knives 134.

The drive sprockets 144 are adapted to withdraw the label sheet 126 along a trough 148 shown in FIG. 2 from a pile of the label sheet which is zig-zag folded on a shelf 150 at the back of the housing 10. As shown in FIGS. 30 and 34 the supporting wheels 154 oppose the hold-down wheels 146 and the hold-down rollers 146^a oppose the supporting wheels 154^a. The rotary knives 134 as shown in FIG. 32 coact with axially spring-biased shear rollers 156 opposed by hold-down rollers 156^a for trimming the perforated margins 132 from the label sheet 126.

The wheels and rollers 154, 154^a and 156, and the drive sprockets 144 are mounted on a shaft 158 which is intermittently driven by a ratchet mechanism 160 shown in FIGS. 33, 35 and 36. A holding pawl mechanism shown generally at 222 is provided for the shaft 158 and is somewhat similar to the ratchet mechanism 120 shown in detail in FIG. 35. The shaft 152 is driven in synchronism with the shaft 158 by a pair of gears shown in FIG. 31.

The ratchet mechanism 160 has an off-center pin 162 driven by a link 164 coacting with the crank pin of a crank 166 on a shaft end 168 of an eccentric shaft 230 (see FIGS. 30 and 33). The shaft 168 as shown in FIGS. 28 and 30 is driven by a belt 170 from a shaft 172 which in turn is driven by bevel gears 174 from a shaft 176. As shown in FIG. 37 there are a series of shafts 178, 180, 182, 184, 186 and 188 driven through a chain of gears and an idler gear 192 from a shaft 190 whereby the shaft 172 rotates simultaneously with the shaft 190.

As shown in FIGS. 15 and 19, the shaft 190, which has the vacuum and heat transfer wheel 60 mounted thereon, is driven by a coupling 194 from a shaft 196. The shaft 196 is driven by a belt 198 from a bevel gear 200 of a differential type adjusting mechanism wherein a second bevel gear 202 is driven by a gear 208 fixed to the bevel gear 202 and meshing with a gear 210 on a drive shaft 212. The drive shaft 212 has a gear 214 thereon meshing with a gear 216 shown in FIG. 3 and located on the shaft 68 driven by the belt 72 from the motor 78.

The differential type adjusting mechanism includes bevel pinions 204 (FIG. 19) carried by a ring gear 206 meshing with an adjusting pinion 214 through the medium of an

idler gear 216. The adjusting pinion 214 is mounted on a telescopic adjusting shaft 218 terminating in an address position adjusting knob 220, the telescopic connection being provided to permit adjustment of the bracket 140 laterally of the table 12 to accommodate different sizes of envelopes and the like being labeled, and to adjust the position of the address or label on the envelope by rotation of the knob 220 as will hereinafter appear.

In FIG. 34 the vertically reciprocable knife 136 is shown coacting with a stationary knife 224. The knife 136 is carried by a vertically reciprocable head bar 226 driven by a pair of connecting rods 228 coacting with the eccentric shaft 230. Adjacent the knives 136 and 224 is a spring biased hold-down bar 232, and guide plates 234 and 236, all provided for the label sheet 126. A trough 238 is provided to receive the label strip 128 after it is sheared from the label sheet 126. Associated with the trough is a leaf spring 239 (see also FIG. 3) adapted to guide the label strip 128 properly into the trough. The trough is on an incline for compactness of design and is interrupted adjacent its lower end by a lower feed roller 240 formed of rubber-like plastic material for gripping efficiency and an upper feed roller 242. The feed roller 240 is mutilated for intermittent feeding and to permit the right-hand end of the label strip 128 in FIG. 28 to enter between the rollers 240 and 242 immediately after it is sheared from the label sheet 126. The feed rollers 240 and 242 coact with the label strip to feed it to cutter rollers 244 and 246. The roller 240 is driven from the shaft 182 by a collar 241 through the medium of a spring 243 as shown in FIGS. 44 and 45 with lost motion limited by a slot 245 and a pin 247.

The upper cutter roller 246 is made of metal and the lower one 244 has a mutilated resilient land 280 from which a pinch-off knife 282 extends (see FIG. 29) to just contact the surface of the roller 242. This requires fine adjustment of the position of the knife 282 accomplished by means of an adjusting wedge 284 and a set screw 286. A lock screw 288 is also associated with a slot in the knife 282 to hold the adjustment once it is made.

Between the feed rollers 240 and 242, and the cutter rollers 244 and 246 is a resilient wire finger 288 carried by a bar 290 pivoted at 292. A spring 296 holds the bar 290 against an adjustable stop screw 294 so that the position of the upper end of the finger 288 may be adjusted substantially as shown in FIG. 28 to guide the label strip 128 to the cutter rollers 244 and 246. A stationary guide element 289 cooperates with the finger 288 in properly guiding the label strip.

The lower feed roller 240 is mounted on the shaft 182 while the lower cutter roller 244 is mounted on the shaft 186 and driven by gears, as explained in connection with FIG. 37, a shaft 298 being shown driven by gears from the shaft 186. The upper cutter roller 246 is mounted on the shaft 298. A cross sectional detail is shown in FIG. 43 wherein is also shown a clutch connection between the shaft 188 and a gear 189 thereon. The clutch connection comprises a clutch disc 191 carrying a clutch pin 193 to enter a clutch pin hole 195 in the gear 189 under the bias of a clutch spring 197. A clutch shifter yoke 187 is actuated by energization of a clutch actuating solenoid 185 shown in FIG. 30 to withdrawn the pin against the bias of the spring.

Details of the vacuum and heat transfer wheel 60 are shown in FIGS. 38 to 42, inclusive. The wheel 60 has a land 300 provided with vacuum ports 302. As shown in FIG. 39, the land extends a little over 90° around the periphery of the wheel. The ports 302 are connected by passageways 304 with manifold cavities 306 which in turn are connected by passages 308 and 310 to lateral ports 312 (see FIG. 38) coacting with partially annular supply ports 314 shown in FIG. 42. The supply ports 314 are evacuated by a vacuum hose 316 extending from a vacuum manifold 317. The arrangement is such that three of the lateral ports 312 coact with the outer supply port 314

as obvious from an inspection of FIG. 39. Two of the passages 310 are provided with shut off valves 318 in the form of set screws as shown in FIG. 41 that can be adjusted to the position shown for full flow, screwed all the way in for complete shut off or part way in for reducing the flow through these two passageways as desired.

The land 300 thus constitutes an arcuate vacuum shoe which is also a heater shoe accomplished by providing the shoe with an imbedded heating element 320, the terminals of which are connected to collector rings 322 and 324. A pair of brushes 326 contact the rings 322 and 324 to furnish them with electricity which then flows through the heating element 320. The wires for the brushes 326 are shown at 334 in FIG. 37.

The supply ports 314 are provided in a port head 328 mounted on the shaft 190 as shown in FIG. 38 but kept from rotating with the shaft by an arm 330. The angular position of the head 328 may be adjusted by means of an arcuate slot 331 in the arm 330 and clamp screws 332 in an obvious manner as shown in FIG. 28.

In FIGS. 46 to 50, inclusive, we show a vacuum pick-off wheel 342 rotated by a shaft 344 driven by gears from the shaft 186 as shown in FIG. 37 through the medium of an idler gear 356. The wheel 342 has vacuum ports 346 which communicate with a vacuum port 348 that rotates past a vacuum port 350 of a port head 352. The port 350 communicates through a hose 354 with the manifold 317 which in turn is connected by a vacuum hose 358 to a vacuum pump 360 shown in FIG. 5 and driven by a vacuum pump motor 362. A label-receiving trough 364 is associated with the vacuum pick-off wheel 342 and a weight 366 rests therein against the labels as shown in FIGS. 51 and 52, and as labels are deposited in the trough the weight is pushed upwardly along the trough in a manner which will hereinafter be described.

Referring to FIGS. 25, 26 and 27, details of the collecting unit 124 are shown. The timing belt 56 discharges the labeled envelopes from the right-hand end (FIGS. 3 and 26) of the housing 10 and onto a take-away conveyor belt 270 which travels very slowly at right angles to the belt 56 and is driven by a belt 272 from a speed-reducer 274 operated by a motor 276 independent of the main drive for the machine. The direction of travel is indicated by the arrow 274 and the envelopes are "shingled" as they are successively deposited on the conveyor belt 270. The shingled envelopes are propelled by the conveyor belt toward an inclined tray 276 and the belt slips under their lower edges as they stack up against the tray from which they may be removed as desired. They may be automatically separated in groups if desired in accordance with the mechanism disclosed and claimed in the copending application of Kirk and Du Four, Ser. No. 460,796, filed June 2, 1965, now Pat. No. 3,458,383. A back plate 278 is adjustably mounted on the collecting unit 124 to prevent the envelopes from falling off the right-hand end of the conveyor belt 270. As shown in FIG. 26 the conveyor belt is laterally inclined so that the envelopes slide down against a fence 271.

In FIGS. 15, 16 and 17 limit switches 368 and 370 for certain functions of the machine are shown. In FIGS. 15 and 18 "STOP" actuates a stop switch 376. In FIGS. 5, 28 and 42, a pressure hose 380 is shown to deliver a puff of air for the purpose of releasing the label as will be later described. The port heads 352 of FIGS. 3, 28, 46, 47, 48 and 50, and 396 of FIGS. 57 and 60 are held against rotation and made adjustable in position in a manner similar to the port head 328 in FIGS. 3, 15, 28, 38, 40 and 42 by the use of an arm 330a similar to the arm 330 shown in FIG. 3.

In order to perform a label gluing operation in our machine, the mechanism illustrated in FIGS. 57 to 60, inclusive, is provided. A glue pot 382 is mounted on a pad 381 of the main bracket 140 in which a glue roller 384 on a shaft 385 dips and then contacts the label 130. The glue pot 382 is fed in fountain fashion from a bottle of glue

386. A special shouldered clamp screw 383 serves to removably mount the glue pot on the main bracket. An adjustable wiper blade 388 is associated with the glue roller 384 to regulate the amount of glue applied to the label.

Instead of the vacuum and heat transfer wheel 60, a vacuum wheel 390 is provided having a land 392 serving as a vacuum shoe to pick up labels from a vacuum operated label transfer wheel 394 substituted for the vacuum pick-off wheel 342. A different type of port head 396 is provided in place of the port head 352 of FIG. 50. The porting therefor is shown in FIG. 30. FIG. 59 illustrates a pair of label pick-up ports 398 provided in the land or vacuum shoe 392.

PRACTICAL OPERATION

In the operation of our addressing machine, the article magazine 14, 16, 18, 20 is adjusted as to horizontal size to fit envelopes, magazines or whatever size of articles are to be labeled. The articles such as envelopes 54 shown in FIG. 7 rests on the slide plate 26 and a pair of sheet metal clips 29 at the back 20 as shown in FIGS. 3, 6 and 7, are withdrawn by the reciprocations of the slide plate 26 and its associated mechanism driven by the connecting rod 28 and the crank pin 30 of the crank arm 32. At the beginning of the forward stroke shown in FIG. 7 the vacuum slide valve 40 is open to the vacuum hose 46 and thereby draws the forward edge of the lowermost envelope 54 downwardly against the vacuum plate 38 thus disengaging it from the vertically adjustable stop bar 110 which retains the rest of the envelopes in the article magazine while the lowermost one is pulled forwardly as shown in FIG. 8 by the forward motion of the vacuum plate 38. By this time the forward edge of the envelope enters between the feed rollers 94 and the land 96 of the feed roller 98 shown in FIG. 3 for positive feed thereby onto the timing belt 56 and under the hold-down rollers 58. The timing belt carries the envelope under the vacuum and heat transfer wheel 60, where the envelope is labeled with an address or the like, and then off the right-hand end of the housing 10 in FIG. 3 and into the take-away conveyor 270 shown in FIG. 25.

One label is supplied to the vacuum and heat transfer wheel 60 for each envelope, the labels being cut at properly timed intervals from the label sheet 126 shown in FIG. 53 by the vertical reciprocations of the knife 136 once each four cycles (for a label sheet 126 which is four labels 130 wide), and the rotation of the feed rollers 240 and 242 in FIG. 28 together with rotation of the cutter rollers 244 and 246 once each cycle. The label sheet 126 is also advanced by the ratchet mechanism shown in FIG. 35 once each four cycles because of the label sheet having four addresses abreast.

As the label strip 128 is advanced by the feed rollers 240 and 242, its forward edge is guided by the resilient fingers 288 and the guide element 289 shown in FIGS. 28 and 51 to pass between the cutter rollers 244 and 246. As the pinch-off knife 282 registers with the cutter roller 246, the label 130 is pinched off as shown in FIG. 52 at the line 138 shown in FIG. 53 and is guided by a shoe 249 to the land 300 of the wheel 60. The vacuum porting described in connection with FIGS. 39, 40, 41 and 42 causes the individual labels 130 to be carried by the land 300 at a surface speed equal to the travel of the envelope 54 as illustrated in FIG. 51 during which time the heat of the shoe caused by energization of the heating element 320 shown in FIGS. 39 and 40 transfers the printing from the carbon side of the label (FIG. 54) onto the envelope 54 as shown in FIG. 55.

The used labels 130 are then picked off the land 300 by 70 the vacuum pick-off wheel 342 as shown in FIG. 52 at which time the porting arrangement for the vacuum wheel 60 releases the label by shut off of the vacuum and delivery of a puff of air from a port 379 (FIG. 42) supplied by a hose 380 extending to the discharge side of the

vacuum pump 360 as shown in FIG. 5. The label is deposited in the trough 364 shown in FIGS. 51 and 52 by release of the vacuum in the pick-off wheel at the time the label has nearly reached the position shown. The successive labels are thus transferred from the wheel 60 to the inclined trough 364 and push the weight 365 upwardly along the trough as they accumulate.

The timing between the timing belt 56 and the vacuum and heat transfer wheel 60 may be changed so as to shift the address on the envelope to the right or left as desired by rotating the address position adjusting knob 220 in the proper direction which changes the angular position between the shafts 212 and 196 shown in FIG. 15. The vertical position of the address on the envelope shown in

15 FIG. 55 may be adjusted by movement of the entire bracket 140 and the parts carried thereby by rotation of the adjusting knob 260 which adjusts the bracket horizontally and laterally with respect to the top 12 of the housing 10 (toward and away from the operator's position in front of a control panel shown in FIG. 1 and the control knobs 220, 260, 262 and 336 thereon). To adjust the machine for thickness of articles such as envelopes at one time and magazines at another, the bracket 140 may be adjusted vertically by the adjusting knob 262 shown in FIG. 18.

Once the labels 130 have been used as illustrated in FIGS. 54 and 55, they cannot be reused in heat-transfer fashion but can be glued to articles as shown in FIGS. 53 and 56. This is accomplished by the setup shown in FIGS. 30, 57, 58, 59 and 60 wherein a stop plate 366 of FIGS. 51 and 52 is removed and the labels 130 can then be removed from the trough 364 by the vacuum operated label transfer wheel 394 of FIG. 57 wherein a label 130 is being transferred from the trough to the vacuum shoe land 392 of the vacuum wheel 390 and will be carried past the glue roller 384 where it picks up a film of glue. The shoe 392 then presses the glued side of the label against the envelope. In this figure three different positions of the vacuum shoe 392 are shown wherein the solid position illustrates transfer from the wheel 394 to the wheel 390, the dot-and-dash line position 392^a indicates the label being glued and the dot-and-dash position 392^b illustrates the label being adhered to the envelope.

The thickness of the film of glue may be nicely regulated by the adjusting screw 389 of the adjustable wiper blade 388. The glue pot 382 may be readily removed for cleaning by means of removing the special clamp screw 383 shown in FIG. 58.

The main bracket 140 and the mechanism supported thereby may be enclosed in a partially transparent cover 142 shown in FIGS. 1 and 2 and omitted from the other figures.

From the foregoing disclosure it will be obvious that we have provided a versatile addressing machine and one 55 which uses heat transfer label sheets from which the labels are cut and can be applied to dual mailing pieces such as magazines and letters, one by heat transfer and the other by gluing the label in position. Automatic means is provided for storing the labels after the heat transfer operation so that they can be subsequently used during the label glue-on operation.

Some changes may be made in the construction and arrangement of the parts of our addressing machine without departing from the real spirit and purpose of our 65 invention, and it is our intention to cover by our claims any modified forms of structure or use of mechanical equivalents which may reasonably be included within their scope.

We claim as our invention:

1. In an addressing machine, a supporting surface for articles, an article magazine thereabove, a timing belt movable along said supporting surface, means for removing articles one at a time from said magazine and delivering them to said timing belt, a vacuum wheel above 75 said timing belt for supporting successive labels and ad-

11

hering them to successive articles carried by said timing belt, means for delivering successive labels to said vacuum wheel, said last mentioned means including an accumulator trough in which cut labels are stacked for use by said vacuum wheel, and transfer means to withdraw one label at a time from said accumulator trough and deliver said labels to said vacuum wheel; and a gluing roller opposing said vacuum wheel and operable to apply glue to the label as the label passes said gluing roller and before it is glued to an article on said timing belt.

2. An addressing machine according to claim 1 in which said transfer means comprises a vacuum operated label transfer wheel interposed between said accumulator trough and said vacuum wheel to pick up the labels one at a time from said trough and deliver them to said vacuum wheel.

3. An article addressing machine according to claim 1 in which said label delivering means includes means for supplying previously used heat transfer labels to said accumulator trough for reuse as glued labels.

4. In an article addressing machine of the type having label transfer means for bringing individual labels into transfer contact with the articles to be addressed and thereby transfer the address information from the label to the article, means for delivering articles to be addressed to said transfer means for addressing thereof, and means for delivering successive labels to said transfer means, the improvement comprising:

means for accumulating the used labels following trans-

12

fer of the address information therefrom for reuse as glue labels; means for withdrawing said used labels from said accumulating means and delivering said used labels in succession to said transfer means for gluing to articles to be addressed; and means for applying glue to said used labels to enable said transfer means to glue said used labels on said articles.

5. The article addressing machine according to claim 4 in which said used label withdrawing means includes a rotatable vacuum pickoff wheel operatively disposed between said used label accumulating means and said transfer means adapted to withdraw said used labels in succession from said accumulating means and deliver said used labels to said transfer means.
